22 Claims

ABSTRACT OF THE DISCLOSURE

This disclosure relates to an apparatus for forming a package from a plurality of articles and a carrier blank which includes apertured panels including means for wrapping the carrier blank about the articles, means for supporting the articles through the apertures of the panels, and the last-mentioned means being in the form of fingers carried by adjacent endless runs of a conveyor. Means are additionally provided for aligning the blank relative to the articles, reorienting the package after the blank has been wrapped thereabout, and inserting end closures into the package to complete the same.

It is relatively well known to form wrap-around type packages from a plurality of articles, such as bottles or cans, by conveying the articles along a predetermined path and progressively wrapping a carrier blank about selected ones of the articles. The carrier blanks are normally individually removed from a hopper and advanced above and in timed relationship with the conveyed articles. Conventional folders, such as rotating blades or discs, progressively fold the individual carrier blanks about the selected articles toward a generally tubular configuration after which, depending upon the carrier blank structure, the carrier blanks are fixed in the generally tubular configuration thereof by, for example, interengageable locking tabs and openings formed in closure panels of the blanks.

Such conventional apparatus is, for the most part, quite acceptable for packaging articles having closures which are entirely removed to gain access to contents packaged therein. However, it has now become common to remove only portions of the end closures of containers, as in the case of easy-open beverage containers, and to drink the contents directly from the containers. The desirability of maintaining the end closures of the containers free of contaminants is achieved in accordance with this invention by means of a package-forming apparatus which removes individual partitions from a hopper and positions each partition upon selected ones of a plurality of containers to both maintain the selected containers in spaced relationship during and after the packaging operation, and additionally maintain the closures of the containers completely covered, thereby preventing dirt or other contaminants from adversely affecting the containers.

A further advantage of the novel apparatus of this invention is the provision of means for supporting the articles or containers during the wrapping of a carrier blank thereabout by a plurality of finger-like elements which pass through apertures in panels of the carrier blank and underlyingly supportingly engage the containers. The finger-like elements are moved in synchronism with the containers and support the containers until the package has been completely formed. This assures that the containers will not be accidentally dislodged from an associated carrier blank during the wrapping operation, as is relatively common in conventional wrap-around type package-forming apparatuses.

Still another object of this invention is to provide a novel apparatus of the type heretofore described wherein

2

means are additionally provided for aligning each carrier blank during its movement with the selected containers whereby interlockable latching tabs and notches can be readily and accurately engaged to maintain the carrier in the final generally tubular configuration thereof. The aligning means are edges of the finger-like elements which contact edges defining the apertures of the carrier blanks during the passage of the elements through the apertures toward a position in underlying supporting relationship to the containers. During this movement, the edges of the finger-like elements forcibly contact the edges of the apertures of misaligned carrier blanks, causing the shifting thereof to an accurate aligned position relative to the containers and the path of travel thereof.

Yet another object of this invention is to provide a novel apparatus for forming a package of the type heretofore described wherein the finger-like elements additionally include means for urging closure panels of the carrier blanks transversely toward each other to tightly wrap each carrier blank about selected ones of the containers. The urging means contact edges of the apertures from opposite opposing transverse directions, forcing the closure panels toward each other and each carrier blank into intimate embracing relationship to its associated containers.

A further object of this invention is to provide a novel package-forming apparatus of the type heretofore described wherein means are provided for rotating each completed package through approximately 90°, and means for thereafter inserting the closure members into axially opposite end portions of the packages to close the end portions whereby containers are precluded from being inadvertently or accidentally removed from the packages and, in the case of clear glass containers housing light-sensitive products, preventing light from adversely affecting such products.

With the above and other objects in view that will hereinafter appear, the nature of the invention will be more clearly understood by reference to the following detailed description, the appended claims and the several views illustrated in the accompanying drawings.

In the drawings:

FIGURE 1-A is a highly schematic side elevational view of a novel package-forming apparatus of this invention, and illustrates means for removing partitions and carrier blanks from associated hoppers, means for positioning each partition upon selected ones of a plurality of conveyed containers, and means for thereafter wrapping a carrier blank about the selected containers to form a generally tubular shaped open-end package.

FIGURE 1-B is a highly schematic side elevational view of another portion of the package-forming apparatus of FIGURE 1-A, and illustrates means for rotating the package 90° relative to a predetermined path of travel, and means for inserting a closure member into each open axial end portion of the tubular carrier blank.

FIGURE 2 is a highly enlarged fragmentary side elevational view partially in section and with parts broken away for clarity of the means for withdrawing the partitions from a hopper and positioning each partition in overlying relationship to selected ones of the containers.

FIGURE 3 is a sectional view taken generally along line 3—3 of FIGURE 2, and illustrates a plurality of rods for guiding the movement of the partitions in the partition hopper.

FIGURE 4 is a fragmentary top plan view taken generally along line 4—4 of FIGURE 2 with parts removed for clarity, and illustrates a pair of endless members for advancing the containers along the predetermined path and longitudinally spacing the containers slightly from each other.

FIGURE 4-A is a schematic fragmentary rear view of a drive arrangement of the partition removing and applying means of FIGURE 2, and illustrates the manner in which synchronous movement is effected between the means for withdrawing the partitions from the hopper and the means for applying the partitions to the containers.

FIGURE 5 is a fragmentary top plan view of the drive arrangement of FIGURE 4-A, and more clearly illustrates the components thereof.

FIGURE 6 is an enlarged fragmentary sectional view taken generally along line 6—6 of FIGURE 2, and illustrates the position of a partition after having been removed from the partition hopper but prior to being applied to the containers.

FIGURE 7 is an enlarged fragmentary sectional view taken generally along line 7—7 of FIGURE 4, and more clearly illustrates a partition positioned between, by a noncontacting relationship to, adjacent pairs of the containers.

FIGURE 8 is an enlarged fragmentary sectional view taken generally along line 8—8 of FIGURE 4, and illustrates another partition positioned between selected ones of the containers after the latter have been urged more closely adjacent one another.

FIGURE 9 is a fragmentary side elevational view with parts broken away for clarity of the carrier blank hopper, and clearly illustrates the means for removing the blanks from the hopper, means for transferring the blanks to a conveyor in overlying relationship to the containers, and means for initiating the folding of the blanks toward a tubular configuration.

FIGURE 10 is a highly schematic partially fragmentary side elevational view of a portion of the apparatus of FIGURE 9, and illustrates a pivotally mounted roller for aiding the movement of the blanks from the transfer means to the carrier blank conveyor.

FIGURE 11 is a sectional view taken generally along line 11—11 of FIGURE 9, and more clearly illustrates the carrier blank folding means and the mechanism for pivoting the roller in synchronism to the carrier blank transfer means.

FIGURE 12 appearing in the sheet including FIGURES 9 and 10 is a highly reduced schematic cross-sectional view taken generally along line 12—12 of FIGURE 11, and illustrates the drive mechanism for the carrier blank transfer means and folding means of FIGURE 9.

FIGURE 13 is a fragmentary top plan view of a portion of the apparatus for folding each carrier about a selected plurality of the containers, and illustrates a pair of endless members having means for supporting the containers through apertures in the carrier blanks and means for urging closure panels of the blanks toward one another to effect a tight wrapping of the blanks about the containers.

FIGURE 14 is an enlarged top plan view of a portion of the mechanism of FIGURE 13, and more clearly illustrates the manner in which the containers are individually supported by finger-like elements carried by the endless members.

FIGURE 15 is an enlarged sectional view taken generally along line 15—15 of FIGURE 14, and illustrates a pair of opposed finger-like elements moving toward each other through apertures in the carrier blank for eventual positioning beneath and in supporting relationship to the containers.

FIGURE 16 is a sectional view taken generally along line 16—16 of FIGURE 15, and more clearly illustrates the passage of one of the finger-like elements through an associated aperture in the carrier blank.

FIGURE 17 is a fragmentary sectional view taken generally along line 17—17 of FIGURE 16, and additionally illustrates the position of the finger-like element during the movement thereof through the aperture of the carrier blanks.

FIGURE 18 is a fragmentary enlarged sectional view taken generally along line 18—18 of FIGURE 14, and illustrates means carried by the finger-like elements for urging closure panels of the carrier blank toward one another, and the initial position of a locking tab of an outer closure panel relative to a tab-receiving opening of an inner closure panel.

FIGURE 19 is an enlarged fragmentary sectional view taken generally along line 19—19 of FIGURE 13, and illustrates the position of another locking tab of the outer closure panel just prior to being forcefully urged between contacting lower end portions of adjacent containers and the finger-like elements in underlying supporting relationship to the containers.

FIGURE 19-A is a fragmentary sectional view taken generally along line 19-A—19-A of FIGURE 13, and illustrates the finger-like elements being retracted from the carrier blank apertures to a position in non-supporting relationship to the containers.

FIGURE 19-B is a fragmentary sectional view taken generally along line 19-B—19-B of FIGURE 13, and illustrates the final interlocked position of the now tubular carrier blank and a latching tab defining a separator between adjacent pairs of the containers.

FIGURE 19-C is a bottom view of the right-handmost portion of the package of FIGURE 19-A, and in phantom outline illustrates one of the finger-like elements during its retracting movement from beneath its associated container.

FIGURE 20 is a fragmentary top plan view taken generally along line 20—20 of FIGURE 19, and illustrates means carried by one of the finger-like elements for aligning the carrier blank relative to the containers and means for urging the carrier blank into intimate embracing relationship with the containers.

FIGURE 21 is a fragmentary sectional view taken generally along line 21—21 of FIGURE 20, and more clearly illustrates the manner in which one of the closure panels is urged toward an opposite closure panel by a portion of the finger-like element.

FIGURE 22 is a fragmentary top plan view with parts removed for clarity of an upstream portion of the package-forming apparatus, and illustrates means for rotating each of the packages 90° prior to inserting closure members into axially opposite open end portions of the now tubular carrier blanks.

FIGURE 23 is a fragmentary top plan view of a portion of the rotating means of FIGURE 22, and illustrates guide means for aligning the packages after the same have been rotated 90°.

FIGURE 24 is a highly schematic fragmentary sectional view taken generally along line 24—24 of FIGURE 23, and illustrates means for conveying the rotated packages toward a closure member applying mechanism.

FIGURE 25 is a fragmentary sectional view taken generally along line 25—25 of FIGURE 22, and more clearly illustrates a turret mechanism for rotating the packages.

FIGURE 26 is a fragmentary top plan view taken generally along the line 26—26 of FIGURE 25, and illustrates the drive mechanism for the package rotating turret mechanism and for a take-away conveyor upstream thereof.

FIGURE 27 is a highly diagrammatic view taken generally along line 27—27 of FIGURE 26, and illustrates means for synchronizing input and take-away conveyors of the turret mechanism.

FIGURE 28 is an enlarged fragmentary sectional view taken generally along line 28—28 of FIGURE 25 with parts broken away for clarity, and illustrates a plurality of vacuum actuated transfer arms of the turret mechanism.

FIGURE 29 is an enlarged fragmentary sectional view taken generally along line 29—29 of FIGURE 25, and illustrates a vacuum chamber and associated ports for

selectively drawing a vacuum through the transfer arms and venting the vacuum arms to atmosphere.

FIGURE 30 is an enlarged sectional view taken generally along line 30—30 of FIGURE 28, and illustrates a plurality of ports cut-off from a vacuum source.

FIGURE 31 is an enlarged fragmentary sectional view taken generally along line 31—31 of FIGURE 29, and illustrates a path of fluid communication established between one of the vacuum transfer arms and a source of vacuum during the initiation of package rotation.

FIGURE 32 is an enlarged fragmentary sectional view taken generally along line 32—32 of FIGURE 29, and illustrates one of the vacuum transfer arms being vented to atmosphere to release a now rotated package.

FIGURE 33 is an enlarged fragmentary sectional view with parts broken away for clarity of an upstream portion of the apparatus beyond the turret mechanism, and illustrates one of two mechanisms for inserting closure members into axially opposite open end portions of the packages.

FIGURE 34 is a fragmentary sectional view with parts broken away for clarity taken generally along line 34—34 of FIGURE 33, and illustrates two pivotally mounted vacuum transfer arms inserting a closure member into each axial end portion of a package.

FIGURE 35 is a perspective view of the closure members, and illustrates hook-like portions for interlocking the closure members with the carrier blanks.

FIGURE 36 is a fragmentary sectional view taken generally along line 34—34 of FIGURE 33 with parts removed for clarity, and illustrates a first vacuum transfer arm for removing a closure member from a hopper, a second cooperative vacuum transfer arm for inserting the closure member into an end portion of a package, and cam means for synchronizing the relative movement between the vacuum transfer arms.

FIGURE 37 is an enlarged sectional view taken generally along line 37—37 of FIGURE 34, and illustrates means for shifting the vacuum transfer arms during the movement of the packages to maintain alignment between the closure members and the packages.

FIGURE 38 is a fragmentary sectional view taken generally along line 37—37 of FIGURE 34, and illustrates a shifted position of the closure member inserting mechanism and the relative position of packages associated therewith.

FIGURE 39 is a fragmentary sectional view taken generally along line 39—39 of FIGURE 37, and more clearly illustrates one of the closure members inserted in an axial end portion of an associated package.

FIGURE 40 is a fragmentary sectional view taken generally along line 40—40 of FIGURE 37, and illustrates the interlocking relationship between the closure member and the associated carrier blank.

FIGURE 41 is an enlarged fragmentary side elevational view of the carrier blank and closure member of FIGURE 40, and illustrates the interlocked relationship between a hook of the closure member and an aperture of the carrier blank.

FIGURE 42 is a fragmentary sectional view taken generally along line 42—42 of FIGURE 41, and more clearly illustrates the interlocked relationship between the closure member and the carrier blank.

FIGURE 43 is a fragmentary sectional view taken generally along line 43—43 of FIGURE 33, and illustrates a cam-actuated mechanism for deflecting a portion of a top panel of the carrier blank into overlying relationship to a portion of the closure member.

FIGURE 44 is an enlarged fragmentary side elevational view of the deflecting mechanism of FIGURE 43, and illustrates the fully deflected position of the top panel portion.

FIGURE 45 is a fragmentary sectional view taken generally along line 45—45 of FIGURE 37, and illustrates components of the mechanism for shifting the closure

member inserting means in time sequence with an associated package.

FIGURE 46 is a sectional view taken generally along line 46—46 of FIGURE 45, and illustrates a reciprocally mounted shaft of the shifting mechanism and a cam operated yoked lever for reciprocating the shaft.

A novel apparatus or machine for forming a package in accordance with this invention is generally designated by the reference numeral 25 (FIGURE 1-A) having a frame 26 adjacent end portions of which are disposed a pair of article in-feed conveyor chains 27, 28 entrained about respective sprockets 30, 31 (FIGURES 1-A and 4). The sprockets 30, 31 are fixed to a shaft 32 (FIGURE 1-A) which is in turn conventionally journaled by means not shown in the frame 26, and driven to impart left-to-right movement to upper runs (unnumbered) of the conveyor chains 27, 28 and articles A, such as bottles or similar containers having necks N and caps or closures C (FIGURE 2). The side rails 33, 34 adjacent the chains 27, 28, respectively, and a center rail 35 cooperate to guidingly feed the articles A in two transversely spaced rows, as is best illustrated in FIGURE 4 of the drawings. It should be particularly noted that during the movement of the articles A by the chains 27, 28 the articles A are generally in contacting relationship (FIGURE 2), and are pushed across a transfer plate 36 of the frame 26 (FIGURE 2) to an upper run of a pair of conveyor chains 37, 38.

The chains 37, 38 are entrained about respective sprockets 40, 41 associated with shafts (unnumbered) journaled in the frame 26.

The function of the chains 37, 38 is to continue the movement of the articles A from left-to-right through means generally designated by the reference numeral 42 (FIGURE 4) for separating the articles or containers A prior to and during the application of an individual partition or divider B upon a predetermined number of the articles A, as will appear more fully immediately hereafter.

The chains 37, 38 are driven from a main motor 43 (FIGURE 1-A) which includes a pulley 44 about which is entrained a pulley belt 45. The pulley belt 45 is in turn entrained about a pulley 46 fixed to a shaft 47 of a gear box 48 having an output shaft (not shown) carrying a sprocket (also not shown) about which is entrained a drive chain 50. The drive chain 50 is in turn entrained about a sprocket (not shown) fixed to the shaft (unnumbered) associated with the downstream side of the chains 37, 38.

The separating means 42 (FIGURE 4) includes a pair of endless chains 51, 52 entrained about associated sprockets 53 through 57 having shafts (unnumbered) suitably journaled in the frame 26 and driven in synchronism by means (not shown) from the main motor 43. The chains 51, 52 are driven in unison by, for example, connecting the output shaft (not shown) of the gear box 48 to the shafts of each of the sprockets 57 to impart left-to-right movement to adjacent runs (unnumbered) of the chains 51, 52. The centers of rotation of the sprockets 53 through 56 are so arranged as to cause the inner runs of the chains to initially converge toward each other during the travel thereof between the sprockets 53, 54, to move in straight line parallel relationship between the sprockets 54, 55 and to thereafter diverge to a movement between the sprockets 55, 56. Due to this construction a plurality of generally triangularly shaped noses or fingers 58 carried by the chains 51, 52 in transversely opposed relationship are progressively positioned between pairs of the contacting articles A (FIGURE 4) causing the same to separate longitudinally as the articles A are moved from left-to-right, in the manner readily apparent from FIGURE 4 of the drawings.

During the separation of the articles A transversely adjacent pairs of the articles A are maintained in spaced relationship by a center rail 60 (FIGURES 4 and 6) which forms a continuation of the center rail 35. However, the center rail 60 includes a pair of side plates 61, 62 (FIGURE 6) secured to each other by suitable fasteners (un-

numbered) and a longitudinally extending bar 63 spaced from the upper edges of the plates 61, 62 to form a longitudinally extending upwardly opening slot 64, the purpose of which will be more apparent hereafter.

The articles A are also guided during their movement through the separating means 42 by side rails 65, 66 (FIGURE 6) which are generally in longitudinal alignment with the respective side rails 33, 34. The side rails 65, 66 include converging portions 67, 68 (FIGURE 4) at the end of the center guide 60 for moving transversely adjacent pairs of the articles A progressively toward each other and into contact with neck-receiving notches S of associated partitions P previously applied to groups of the articles A.

A mechanism for applying the partitions P to the articles A is best illustrated in FIGURES 2, 4-A and 5, and is generally designated by the reference numeral 70. The mechanism 70 is carried by a plate 71 which is in turn secured by brackets (unnumbered) to the frame 26. An inclined hopper 72 is fixed to the plate 71 in the manner clearly illustrated in FIGURE 3 of the drawings, and includes four cylindrical guide rods 73 through 76 which are guidingly embraced by endmost ones of the notches or slots S of the partitions P. The rods 73 through 76 thereby serve to actively guide a stack of the partitions or dividers P toward a mouth or gate 77 of the hopper 72 in which is located a pair of opposed fingers 78, 80 disposed along the longitudinal center line of the partitions P and spaced apart a distance slightly less than the longitudinal length of the partitions. Thus, the stack of partitions are supported by the fingers 78, 80, but a lowermost one of the partitions which are preferably constructed of resilient material, such as paperstock or plastic material, may be temporarily deflected and removed past the fingers 78, 80 while remaining non-deflected partitions are maintained in the position illustrated in FIGURE 2 by the fingers 78, 80.

The lowermost partition in the hopper 72 is removed through the upper mouth 77 by a vacuum transfer arm 81 (FIGURES 2, 4-A and 5) fixed to a shaft 82 which is in turn journaled in the plate 71. The vacuum transfer arm 81 includes a pair of vacuum cups 83, 84 which are placed in fluid communication with a conventional rotary vacuum valve 85 by a flexible conduit 86. The rotary vacuum valve 85 is in turn placed in fluid communication with a conventional source of vacuum, such as a vacuum pump (not shown), and operates to draw a vacuum during the movement of the vacuum transfer arm 81 from the leftmost phantom outline position of FIGURE 2 to the solid line position in the same figure. In this manner an individual partition P is gripped securely and withdrawn from the hopper 72 during the counterclockwise movement of the vacuum transfer arm 81, as is readily apparent from FIGURE 2 of the drawings. It should be particularly noted that the vertical plane in which the vacuum transfer arm 81 swings is offset from the longitudinal center line of a chain 87 (FIGURE 6) for a reason which will be apparent hereafter, and that the vacuum cups 83, 84 contact each partition P (FIGURE 6) above and below a first finger-receiving opening O1 and remote from a second finger-receiving opening O2.

The vacuum transfer arm 81 is pivoted in synchronism with the other components of the machine 25 by a chain driven bellcrank mechanism (FIGURE 4-A) which includes an arm 90 affixed to the shaft 82 at a side of plate 71 opposite the arm 81 (FIGURE 5). The arm 90 is pivotally connected to a crank rod 91 at 92, while an opposite end portion of the crank arm 91 is pivotally connected at 93 to a disk 94 fixed to a shaft 94 which is in turn conventionally journaled for rotation in the plate 71. A sprocket 96 is fixed to the shaft 95 and a chain 89 is entrained about the sprocket 96 and sprockets 97 through 103 having respective shafts 104 through 110 journaled in the plate 71. A sprocket 111 is fixed to the shaft 109 and a chain 112 coupled to the main motor 43

by means not shown is entrained about the sprocket 111 to impart clockwise rotation thereto, as viewed in FIGURE 4-A. The clockwise rotation of the sprocket 111, the shaft 109 and the sprocket 102 impart similar clockwise rotation to the chain 89, the sprocket 96 and the disk 94 to pivot the vacuum transfer arm 81 between the phantom line positions of FIGURE 2 whereupon the partitions P are individually removed from the hopper 72 and transferred to a partition applying mechanism 120.

The partition applying mechanism 120 includes the chain 87 which is entrained about a plurality of sprockets 121 through 125 carried by respective shafts 126, 127, the shafts 109, 130 and 131, all of which except the shaft 126 are journaled for rotation in the plate 71. The shaft 126 is fixedly secured to the plate 71 and the sprocket 121 rotates freely about the shaft 126.

The chain 87 of the mechanism 120 includes a plurality of fingers 132 which progressively enter the lowermost finger-receiving opening O2 (FIGURES 2 and 6) during the counter-clockwise rotation of the chain 87, as viewed in FIGURE 2 of the drawings, to progressively strip the partitions P from the vacuum cups 83, 84 of the vacuum transfer arm 81 at the time the vacuum begins to break by the closing of the rotary vacuum valve 85 to transfer each partition to a pair of guide plates 140, 141 (FIGURES 2 and 6) which are inclined toward the center guide rail 60. The plate 140 is secured directly to the plate 71 (FIGURE 6) while the plate 141 is connected to an arm 142 which is in turn fixed to the non-rotatable shaft 126. Guide plates 140, 141 are also spaced an appreciable distance from the other to permit the pins or fingers 132 to pass freely therebetween as the partitions P are transferred to the guide plates 140, 141 in the manner readily apparent in FIGURES 2 and 6 of the drawings.

A driven roller 145 having a radially outwardly opening circumferential groove 146 is positioned between the guide plates 140, 141 for directing the leading edge of each partition P down and to the right as viewed in FIGURE 2 of the drawings upon the contact of the knurled peripheral surface (unnumbered) of the roller 145 with each partition. The roller 145 is fixed to a shaft 147 which is in turn journaled in the plate 71. A sprocket 148 (FIGURE 4-A) is fixed to the shaft 147 and a chain 150 is entrained about the sprocket 148 and a sprocket 151 fixed to the shaft 108. The counter-clockwise rotation of the sprocket 148 in FIGURE 4-A is, of course, clockwise rotation which is imparted to the roller 145 in FIGURE 2 to effectively direct each partition in the manner heretofore described. The circumferential groove 146 is also of a sufficient depth to receive the fingers 132 of the mechanism 120 to prevent any jamming from occurring during the transfer of the partitions P.

The synchronous operation of the mechanism 42 and the mechanism 120 assures that each partition P will be positioned between the two rows of spaced articles with the slots S in alignment with the bottle necks N, and with each partition P supported upon the upper longitudinal edges (unnumbered) of the plates 61, 62, as is best illustrated in FIGURES 4 and 7 of the drawings. During the movement of the partitions along the edges of the plates 61, 62 the finger 132 associated with each partition P is freely received in the gap 64 of the central guide 60, as shown in FIGURE 7 of the drawings to prevent jamming between the center guide 60 and the mechanism 120. In addition, each of the partitions P is held firmly upon the upper edges of the plates 61, 62 by a pair of disks 155, 156 arranged on either side of the sprocket 125 and larger disks 157, 158 associated with the sprocket 124. After the fingers 132 are withdrawn from the partitions during the movement thereof along the portion of the chain run between the shafts 130 and 109, the partitions P are moved with the articles A as the latter are advanced by the conveyor chains 37, 38. As the articles

A reach the converging portions 67, 68 of the respective side guide rails 65, 66, the transversely adjacent pairs of the articles A are urged progressively toward each other until the necks N thereof register with an associated one of the slots S, as is best illustrated in FIGURE 4 of the drawings.

Upon passing beyond the conveying portions 67, 68 of the side rails the groups of articles A with a partition P associated therewith are conveyed by the chains 37, 38 beneath a mechanism 160 (FIGURES 1-A and 9) which removes a wrap-around type carrier blank B from a hopper 161 and conveys each blank B to a point at which the blank is united with the groups of articles. Before describing the mechanism 160, reference is made to FIGURE 11 of the drawings and the following description of one of the blanks B. Each of the blanks B includes a top panel 170 set out between a pair of transverse fold lines 171, 172. The top panel 170 includes a plurality of circular openings 173 for receiving the necks N of the articles A. A side panel 174 is defined between the fold line 171 and a discontinuous fold line 175, while another side panel 176 is defined between the fold line 172 and a discontinuous fold line 177. Three identical apertures or openings 178 are formed in each of the side panels 174, 176, and each aperture 178 includes an edge 180 which is substantially parallel to the direction of travel of the blank B, as is indicated by the unnumbered headed arrow in FIGURE 11, an edge 181 normal to the line of blank travel, and an edge 182 disposed at an angle to the direction of blank travel. Two edges 183, 184 are generally in alignment with each other and are each positioned parallel to the direction of blank travel. The function of the various edges of each of the apertures 178 will be more apparent hereafter.

A closure panel 185 having openings 186 is joined to the side panel 174 along the fold line 175 while another closure panel 187 having projecting latching tabs 188 is joined to the side panel 176 along the fold line 177. After each blank B is wrapped about a selected group of the articles A the tabs or tongues 188 are inserted through associated ones of the openings 186 to secure the articles, a partition and an associated blank B in a unified package in a manner to be described more fully hereafter.

The mechanism 160 includes a pair of side plates 190, 191 (FIGURES 1-A and 11) which are secured to the frame 26 by suitable brackets 192, 193, etc. The plates 190, 191 include upstanding leg portions 194, 195 (FIGURE 9), respectively which are spaced from a plate 196 fixed to and projecting above the plates 190, 191. The hopper 161 (FIGURE 9) is supported in part by the upstanding leg portions 194, 195 and the plate 196. The first part (unnumbered) of the hopper 161 includes a generally U-shaped bracket 197 having a bight portion (unnumbered) secured to the plate 196 and a pair of arms 198, 200 directed toward the respective upstanding leg portions 194, 195. An arm 201, 202 is secured to the respective arms 198, 200 in downwardly inclined relationship, and a transversely extending plate 203 is fixed to the ends (unnumbered) of the arms 201, 202. Lowermost edges (unnumbered) of the blanks B are guided upon the upper edges (also unnumbered) at the arms 201, 202, in the manner clearly illustrated in FIGURE 9 of the drawings.

The other part of the hopper 161 includes a bar 205 secured to the plates 194, 195. A cylindrical rod 206 is supported in generally parallel relationship to the arms 201, 202 by each of a pair of brackets 207, only one of which is illustrated, fixed to the bar 205. A transversely extending plate 208 connected between the brackets 207, 208 forms an upper stop for the edges of the blanks B. The arms 201, 202 thereby serve as guides for the stack of blanks B while the plates 203, 208 prevent all but a foremost one of the blanks from being withdrawn from the hopper 161 in the manner heretofore described relative to the hopper 72.

Individual one of the wrap-around blanks B is removed from the hopper 161 by a pair of pivotally mounted vacuum transfer arms 210 (only one of which is shown) fixed to a shaft 211 journaled for rotation in a conventional manner in the upstanding leg portions 194, 195 of the respective plates 190, 191. Each of the vacuum transfer arms 210 carries a pair of vacuum cups 212, 213 which are placed in fluid communication with a vacuum source (not shown) by means of a flexible conduit (not shown) and a conventional rotary valve, such as the rotary vacuum valve 85 (FIGURE 5). The rotary vacuum valve associated with the vacuum transfer arm 210 is operative to place the vacuum source in fluid communication with the vacuum cups 212, 213 when the latter contact the forwardmost blank B in the hopper 161 to remove this blank as the arm 210 is swung or pivoted in the direction of the unnumbered headed arrow in FIGURE 9 of the drawings. After the arm 210 and the blank carried thereby passes beyond a vertical position the vacuum valve cuts off fluid communication to the vacuum source and opens fluid communication between atmosphere and the vacuum cups 212, 213 whereupon the blank is stripped from the vacuum cups in a manner to be described hereinafter.

The vacuum transfer arms 210 are simultaneously pivoted toward and away from the blanks in the hopper 161 by a bellcrank mechanism which includes an arm 215 fixed to the shaft 211 (FIGURE 9). A pivot pin 216 (FIGURES 9 and 11) connects the arm 215 to a crank arm 217 which is in turn pivotally connected in an off-center relationship to a disk 218 fixed to a shaft journaled for rotation in the plate 190. A sprocket 221 is fixed to the shaft 220 while another sprocket 222 is fixed to a shaft 223 journaled between the plates 190, 191. A chain 224 is entrained about the sprockets 221, 222. Another sprocket 225 (FIGURE 11) fixed to the shaft 222 imparts rotation to the latter from the motor 43 by a conventional drive mechanism (not shown).

Each blank B is transferred from the vacuum transfer arms 210 to an upper run 226 of a pair of transversely spaced conveyor chains 227, 228 (FIGURES 9 and 13). The conveyor chains 227, 228 are each entrained about sprockets 230, 231 which are affixed to shafts 232 journaled in a conventional manner between the plates 190, 191. The shaft 232 illustrated to FIGURE 9 is driven by a conventional means (not shown) from the main motor 43 to impart clockwise rotation to the shaft, each of the sprockets 230, the chains 227, 228, and left-to-right movement of the upper runs 226 and transversely aligned lugs 235 carried thereby. The lugs 235 engage the trailing edge of each blank B after the transfer thereof from the vacuum transfer arms 210 and continue the left-to-right movement of the blanks in generally superimposed relationship to the articles A in the partitions B, in the manner best illustrated in FIGURE 9 of the drawings.

Prior to the blanks B being engaged by the lugs 235 the leading edge of each of the blanks B is directed toward the bight of a pair of rolls or rollers 236, 237 (FIGURES 9 and 11). The roll 236 is formed of resilient polymeric material, such as rubber, and is freely rotatably mounted on a shaft 238 of an arm 240 which is in turn fixed to a non-rotatable shaft 241 fixedly secured between the plates 190, 191 (FIGURE 11). The roll 237 is fixed to a shaft 242 which is journaled for rotation between the plates 190, 191 and has fixed thereto a sprocket 243. A chain 244 is entrained about the sprocket 243 and a sprocket 245 fixed to a shaft 246 journaled only in the plate 191 (FIGURES 11 and 12). A smaller sprocket 247 is also fixed to the shaft 246. The lower run (unnumbered) of a chain 248 is in mesh with the teeth (unnumbered) of the sprocket 247 and is entrained about sprockets 250, 251, the latter of which is fixed to the shaft 223. The sprocket 250 is fixed to a shaft 249 journaled in the plate 191. Counter-clockwise rotation of the shaft 223 imparts clockwise rotation to the shaft 246 (FIGURE 12) through

the chain 248 which in turn rotates the shaft 242 and the roller 237 in the direction of the unnumbered headed arrow associated therewith in FIGURE 9 to assure that the leading edge of each of the blanks B is fed from left-to-right in FIGURE 9 by the cooperative action of the roller 237 and the roller 236.

Means are also provided to direct the leading edge of the blank B toward the bight between the rollers 236, 237 as each blank is released from the vacuum transfer arms 210. The latter means, generally designated by the reference numeral 255 (FIGURES 9 and 11) includes a roller 256 mounted for pivoting movement about the axis of a rocket shaft 257 from the position illustrated in FIGURE 9 in the direction of the unnumbered headed arrow for engaging the leftmost surface of the lowermost edge of the blank carried by the arms 210 to direct this leading edge toward the bight between the rollers 236, 237. The roller 256 is freely rotatably journaled to the end of an arm 258 which is in turn fixed to the shaft 257. The shaft 257 is journaled between the plates 190, 191 (FIGURE 11) and is pivoted toward and away from the roller 236 by a cam operated bellcrank mechanism which includes an arm 260 fixed to the shaft 257. The arm 260 is connected to an arm 261 by a crank arm 262. The arm 261 is in turn fixed to a shaft 263 which is journaled in the plate 190 and projects through opposite sides thereof, as is best illustrated in FIGURE 11 of the drawings. A crank arm 265 is fixed to the shaft 263 on the side of the plate 190 opposite the arm 261, and an arm 266 is pivotally connected between the arm 265 and a rod (FIGURES 1-A and 11) pivoted at 268 to the plate 190. A spring 270 is connected between the rod 267 and a bracket 271 fixed to the plate 190 to normally bias the rod 267 in a clockwise direction as viewed in FIGURE 1-A of the drawings. A cam follower 272 carried by the rod 267 engages the peripheral surface (unnumbered) of a cam 273 fixed to the shaft 223. The cam 273 includes a flat portion 274 which permits the rod 267 to pivot clockwise (FIGURE 1-A) under the influence of the spring 270 as a leading edge of a blank carried by the vacuum transfer arm 210 passes beyond the periphery of the roller 256. The clockwise pivoting of the rod 267 rotates the shaft 263 in a clockwise direction which in turn imparts clockwise pivoting movement to the arm 258 carrying the roller 256 whereupon the latter moves to the position illustrated in FIGURE 10 and aids in directing the leading edge of each blank B between the rollers 236, 237. After the low portion 274 of the cam 273 passes the follower 272 the high portion (unnumbered) of the cam urges the rod 267 in a counter-clockwise direction as viewed in FIGURE 1-A to retract the roller 256 from the position shown in FIGURE 10 to the position thereof illustrated in FIGURE 9.

After each blank B passes through the bight of the rollers 236, 237 a pair of rollers 270, 271 (FIGURE 11) freely rotatably carried by the shaft 241 maintain each blank of the upper chain run 226 of the chains 227, 228 during the continued left-to-right movement thereof by the lugs 235 toward a pair of folders or folding blades 279, 275 carried by respective arms 276, 277 (FIGURE 11) fixed to the rotatable shaft 223. Each of the blades 279, 275 includes a curved leading edge portion 278 which contacts the side panels 174, 176, respectively, and urges these panels downwardly in a generally vertical plane, as shown best in FIGURE 9 of the drawings.

After the side panels 174, 176 have been folded about the respective fold lines 171, 172 each blank B is guided over a group of the articles A and a partition P associated therewith by a curved guide member 280 (FIGURE 1-A) secured in a conventional manner between the plates 190, 191. The guide member 280 directs the leading edge of each of the blanks B downwardly to effect engagement between the article necks N and the apertures 173 in the top panel 170. During the application of the blanks B to the articles A by the guide plate 280 the articles A are

supported in part by a central supporting plate 281 of the frame 26 positioned between the conveyor chains 37, 38 (FIGURE 13) and projecting downstream beyond the sprockets 41 of FIGURE 13. As is best illustrated in FIGURE 15, transversely adjacent pairs of the articles A are supported only along innermost bottom edges thereof adjacent the longitudinal center line of the supporting plate 281.

The assembled group of articles A, the partition P and the blanks B associated therewith are conveyed along the central supporting plate 281 by conveying means 290, (FIGURES 1-A, 13 and 14) defined by a pair of conveyor chains 291, 292 each carrying generally hook-like fingers 293. The fingers 293 of the innermost runs (unnumbered) of the conveyor chains 291, 292 contacting trailing edges of the vertically depending side panels 174, 176 of each blank B to advance the blanks near the articles A associated therewith from left-to-right in the direction of the unnumbered headed arrow associated with the centermost group of articles in FIGURE 14 of the drawings. Horizontally disposed guides 294, 295 (FIGURES 13 and 14) forming a portion of the frame 26 guide the innermost adjacent runs of the respective conveyor chains 291, 292.

The drive chain 291 is entrained about sprockets 296, 297, 298, 299 (FIGURE 22) and 300 each including a respective shaft 301 through 305 journaled in a conventional manner in the frame 26 for rotation about a vertical axis. For purposes of clarity the individual sprockets 30 and shafts associated with the conveying chain 292 have not been numbered but the conveying chain 292 includes an identical number of sprockets and shafts correspondingly located relative to the frame 26 on the opposite side of the central supporting plate 281.

The conveyor chain 291 is driven in a clockwise direction as viewed in FIGURES 13 and 14 of the drawings by coupling the shaft 301 (FIGURE 1-A) of the sprocket 296 to the gear box 48. The corresponding shaft of the conveying chain 292 is similarly coupled in a conventional manner by means not shown to the gear box 48 to impart counter-clockwise rotation to the conveying chain 292, as viewed in FIGURE 13 of the drawings. Thus, the conveying chains 291, 292 are driven in synchronism with the innermost runs (unnumbered) moving left-to-right as viewed in FIGURES 13 and 14 to continue the advance of the grouped articles A and associated partitions and blanks beyond the conveying chains 37, 38.

Throughout the movement of the grouped articles by the conveying means 290, side rails 307, 308 (FIGURES 13 and 15) positioned above the inner runs of the respective conveying chains 292, 291 support the partially packaged articles in the manner clearly illustrated in FIGURE 15 of the drawings. The rails 307, 308 are conventionally secured to the frame 26 and extend the entire length of the innermost runs of the conveying means 290.

The machine 25 includes means generally designated by the reference numeral 310 for supporting each of the articles A by the bottoms (unnumbered) thereof during the movement of the articles by the conveying means 290 beyond a reduced end portion 311 of the central supporting plate 281. The supporting means 310 includes a pair of chains 312, 313 which carry a plurality of individual bracket means 314 (FIGURES 17 and 20). Each bracket means 314 includes a relatively narrow and thin horizontally disposed supporting finger 315 secured by conventional bolts 316, 317 (FIGURE 17) to a generally rectangular and thicker block member 318 which is in turn conventionally fastened to its associated chains 312, 313. Each supporting finger includes an upper supporting surface (unnumbered) and a convex smoothly rounded terminal edge 320 while a face 321 of the member 318 is flat and disposed in a generally vertical plane (FIGURE 18). The upper surface of the finger 315 is also

flush with the upper surface (unnumbered) of the member 318.

The chain 313 (FIGURE 13) is entrained about a plurality of sprockets 325 through 330 which are in turn fixed to the unnumbered shafts associated with the conveying chain 292 and corresponding to the respective shafts 301 through 305 of the conveying chain 291. The chain 312 is similarly entrained about an identical number of sprockets of which only a sprocket 331 (FIGURE 1-A) fixed to the shaft 301 is specifically designated by a reference character. The sprockets 325 and 331 coupled to the shafts 301 driven by the gear means 48 (FIGURE 1-A) thereby constitute the drive means for imparting left-to-right movement of the inner adjacent runs of the chains 312, 313 as viewed in FIGURES 13 and 14 of the drawings.

As each group of articles A encased in the partially folded blanks B are conveyed along the wider portion of the central supporting plate 281 the transversely aligned bracket means 314 are guided toward an associated aperture 178 in each of the side panels 174, 176 of the blanks B by the converging portion of the inner chain runs between the sprockets 330, 329. During this movement of transversely adjacent bracket means 314 toward each other (FIGURE 15) each finger 315 progressively enters a blank aperture 178, as indicated by the unnumbered headed arrows in FIGURE 15, until each article A is supported upon the upper supporting surface (unnumbered) or of associated finger 315 (FIGURE 18) and partially upon the supporting surface of the associated member 318.

If the blank B is not properly seated upon the group of articles A and the apertures 178 in the side panels 174, 176 are not in exact alignment the curved edge 320 of the fingers 315 will contact either the edge 182 or the edge 181 of the blank apertures 178 and shift the misaligned blank B to a position of alignment at which the apertures 178 in the side panels 174, 176 are in transverse alignment. This assures that the tongues 188 and the latching apertures 186 are similarly in alignment to facilitate eventual interlocking engagement therebetween, and also provides for an effective interlock between lowermost portions of the articles A and the material of the side panels surrounding the apertures 178, in the manner best illustrated in FIGURE 19 of the drawings.

As each group of articles A supported by the individual bracket means 314 are advanced from left-to-right toward the narrow portion 311 of the central supporting plate 281 the closure panel 185 contacts a folded plate 330 (FIGURES 13 and 15) which progressively folds the closure panel 185 along the fold line 175 to a position in generally underlying relationship to the left row of articles, as viewed in FIGURES 15 and 18 of the drawings. Thereafter the closure panel 187 is progressively folded by another folded plate 331 toward a position in underlying relationship to the folded closure panel 185. The folded plates 330, 331 are supported from a generally upstanding plate 332 (FIGURE 15) of the framework 26. During the folding of the closure flaps 185, 187, the continued movement of the bracket means 314 causes the flat faces 321 thereof (FIGURES 18 and 20) to contact the edges 183, 184 of the blank apertures 178 and force the closure panels toward one another causing each blank to be tightly wrapped about an associated group of articles. Thus, each group of articles is tightly wrapped in an associated blank prior to latching engagement between the latching apertures 186 and the tongues 188 in a manner to be described hereafter.

Since the individual brackets 314 of the chains 312, 313 might otherwise tend to deflect downwardly as each blank is wrapped about a group of the articles, a rail 335 adjacent the innermost run of the chain 313 and a rail 336 adjacent the innermost run of the chain 312 underlie the bracket means 314 along a portion of the length of the inner runs between the sprockets 329, 328 (FIG-

URES 13 and 18). The rails 335, 336 are secured in a conventional manner by means (not shown) to the frame 26 of the apparatus 25. The same portions of the innermost conveyor runs are backed up by adjustable guides 337, 338 which are disposed between the sprockets 329, 328 (FIGURE 13) of each of the chains 312, 313, and are adjusted toward and away from each other by screws 340 passing through elongated slots 341 in the guides 337, 338 and threadably received in a portion of the frame 26. The guides 337, 338 resist any tendency of the adjacent runs of the chains 313, 312 to be deflected away from each other during the wrapping and latching operations.

In addition to the various components heretofore described which assure the tight wrapping of the articles A in a selected blank B, the apparatus 25 includes a pair of rails 345, 346 (FIGURE 15) which are supported above the respective rails 307, 308 by conventional means (not shown), such as brackets fixed to the frame 26. The rails 345, 346 correspond in length and position to the rails 335, 336 and extend generally between the sprockets 329, 328 associated with each of the chains 312, 313. A plurality of rollers or rolls 347, 348 are spaced along the rails 345 in transversely opposed relationship to each other and in overlying relationship to portions of the top panel 170 of each blank. The rolls 347, 348 (only one of which is illustrated) maintain the top panel in intimate contact with the shoulders (unnumbered) of the articles A during the folding of the closure panels in the manner heretofore described and the subsequent latching of the tongues 188 and associated latching openings 186.

After each blank is wrapped about an associated group of the articles A and the closure panels are generally in overlapped relationship to each other, the group of articles are conveyed through a latching station, generally designated by the reference numeral 350 (FIGURES 13, 18, 19, 19-A and 19-B). The latching station 350 corresponds generally in structure and function to that disclosed in commonly assigned Patent No. 2,986,857 issued June 6, 1961 in the name of Henry Ganz. A complete description of the structural details of the latching station 350 is therefore deemed unnecessary for a complete understanding of this invention, but it should be noted that prior to the completion of the latching operation the bottom end portions (unnumbered) of transversely adjacent articles A are in contacting relationship (FIGURES 18, 19 and 19-A), while at the completion of the latching operation (FIGURE 19-B) each latching tongue 186 is forcibly introduced between transversely adjacent articles A to force the same away from each other and thereby additionally tighten each latched package which is generally designated by the reference character P' (FIGURE 19-B).

The latched packages P' are progressively transferred by the conveying chains 291, 292 to an upper run 360 of a pulley belt 361 (FIGURES 1-B, 22, 25 and 26). The conveying belt or pulley belt 361 is entrained about a pair of pulleys 362, 363 (FIGURE 26). The pulley 362 freely floats on a shaft 364 which is journaled in side plates 365, 366 of the frame 26. The pulley 363 is keyed to a shaft 367 which is similarly conventionally journaled in the plates 365, 366. An end of the shaft 367 carries a sprocket 368 (FIGURES 26 and 27) which is rotated in a clockwise direction as viewed in FIGURE 27 to impart left-to-right movement to the upper run 360 of the pulley belt 361 to feed the latched packages P' from left-to-right as viewed in FIGURE 25 of the drawings.

The sprocket 368 is driven in synchronism with the other components of the apparatus 25 heretofore described from the main motor 43 by means of a drive chain 380 (FIGURES 1-A and 1-B) entrained about a sprocket 381 coupled to an output shaft (unnumbered) of the main motor 43 and a sprocket (not shown) of a gear box 383 having output shafts 384, 385 (FIGURES 1-B and 25) and respective sprockets 386, 387 keyed thereto. A chain 388 is entrained about the sprocket 387

and a sprocket 390 fixed to a shaft 391 (FIGURES 25 and 26) journaled in the plates 365, 366 of the frame 26. A sprocket 392 is fixed to an end of the shaft 391 projecting outwardly of the plate 366 (FIGURES 26 and 27), and a chain 393 is entrained about the sprocket 392, the sprocket 368 and a sprocket 394 fixed to an end of a shaft 395 beneath the shaft 367 which is similarly journaled in the plates 365, 366. The direction of rotation of the various sprockets and drive chains just described are diagrammatically illustrated by the unnumbered headed arrows in the drawings to effect the left-to-right movement of the packages P' in FIGURE 25 by the conveyor belt 361 toward a package rotating mechanism, generally designated by the reference numeral 400, which will be described more fully hereafter.

During the advancement of the packages P' toward the mechanism 400 a timing chain 401 times the advancement of the packages P' to the mechanism 400. The timing chain 401 carries a plurality of generally L-shaped lugs 402 which project slightly above the upper run 360 of the pulley belt 361 along the upper horizontal run 403 of the timing chain 401 (FIGURE 25). The timing chain 401 is positioned to one side of the pulley belt 361 (FIGURE 26), and is entrained about sprockets 405, 406, 407 and 408 (FIGURE 25). The sprockets 405, 406 float on the respective shafts 364, 367 while the sprocket 407 is keyed to the shaft 395. The sprocket 408 similarly floats on a shaft 410 (FIGURE 25) which is journaled for rotation in the plates 365, 366 (not shown).

Clockwise rotation is imparted to the timing chain 401 to move the upper run 403 from left-to-right in FIGURE 25 by the main motor 43, the gear box 383 and the various sprockets, drive shafts and chains which impart rotation to the sprocket 390, the shaft 391, the sprocket 392 (FIGURES 26 and 27) and the chain 393 entrained about the sprocket 394. As the sprocket 394 is rotated clockwise (FIGURE 27) the shaft 395 imparts similar clockwise rotation to the sprocket 407 (FIGURE 25) to drive the timing chain 401 in the same direction as the pulley belt 361 but at a slower speed. Due to this difference in speeds the leading edge of each package P' carried by the upper run 360 of the pulley belt 361 catches up and eventually contacts one of the lugs 402 of the timing chain 401 prior to reaching the mechanism 400. Thereafter the timing chain 401 controls the delivery of the packages P' to the mechanism 401 in time relationship thereto as will appear more fully hereafter.

The package rotating mechanism 400 consists of a rotatable head 425 fixed to a vertical shaft 426 and a stationary head 427 secured by brackets 428 to an overhead portion 430 to the frame 26. A chain 431 (FIGURES 25 and 26) entrained about the sprocket 386 of the gear box 383 and a sprocket 432 fixed to the vertical shaft 426 imparts counterclockwise rotation to the rotatable head 425 in synchronism with the movement of the packages P by the timing chain 401.

The rotatable head 425 of the mechanism 400 includes an uppermost circular plate 440 (FIGURES 25 and 30-32), an enlarged circular intermediate plate 441 and a flanged collar 442. The plates 440, 441 and the flanged collar 442 are secured to each other by a plurality of circumferentially arranged bolts 439, only one of which is illustrated, in a manner readily apparent from FIGURE 30 of the drawings. A key 443 and a setscrew 444 secure the flanged collar and the plates 440, 441 fastened thereto to the vertical shaft 426.

The plates 440, 441 and the flanged collar 442 include a plurality of axially aligned bores 446-448 (FIGURE 30) each group of which defines a port or passage 450 opening through the upper face (unnumbered) of the plate 440 and the lower face (unnumbered) of the flanged collar 442. There are six such passages 450 formed in the rotatable head 425 in equal circumferential spaced relationship from each other, and each port 450 is spaced an identical radial distance from the axis of the vertical

shaft 426. A threaded fitting 451 is connected to the bore 448 of each passage 450 and a conduit 452 extends from each fitting 451 to an associated vacuum or suction cup 453 carried by a bracket 454 secured to and depending from the plate 441. The purpose of the vacuum cups 453 is to grip the side wall 174 (FIGURE 22) of each latched package P' incident to the rotation thereof through 90 degrees in a manner to be described more fully hereafter. The brackets 454 are therefore secured to the plate 441 in a manner which presents each vacuum cup 453 into face-to-face generally parallel relationship with the side panel 174 of an associated package at the moment of contact to assure that the package is securely gripped and held during its reorientation.

15 A plurality of cylindrical rods 455 are secured to the plate 441 by conventional fasteners 456. There are six rods 455 spaced in equal circumferential distance from each other, and each rod 455 is spaced equally from the axis of the shaft 426. The rods 455 and the vacuum cups 453 are arranged in cooperative pairs with the vacuum cup being effective to grip a leading edge of the package substantially simultaneously with its associated rod 455 contacting a trailing edge of the same package, as is readily apparent from FIGURE 22 of the drawings. The rods 20 455 serve as supports for pushing the packages P' to an oriented position during the rotation of the head 425, and also prevent each package from breaking contact with its 25 associated vacuum cup during the reorienting operation.

The stationary head 427 of the mechanism 400 includes 30 an uppermost circular plate 460 (FIGURE 30) and a lower smaller circular plate 461 securely fastened together by a plurality of bolts 462 (FIGURE 30), only one of which is shown in the drawings. A bushing 463 is press-fit in apertures (unnumbered) in the plates 460, 35 461 and rotatably receives an upper end portion (unnumbered) of the vertical shaft 426. The bushing 463 thereby serves as a journal for the shaft 426 and the rotatable head 425 fixed thereto.

The plate 461 (FIGURE 29) is provided with an ar- 40 cuate circumferentially extending slot 465 having a longitudinal center line spaced from the axis of the shaft 426 at a radial distance equal to the radial distance between the axis of the ports 450 and the shaft 426. As the rotatable head 425 rotates counter-clockwise as viewed 45 in FIGURE 29 each port 450 of the rotatable head is progressively brought into fluid communication with the slot 465, passes a narrow bridging portion 466, is progressively placed into fluid communication with a slot 467 of the plate 461 and subsequently passes beyond the slot 50 467. The slots 465, 467 are connected to a conventional vacuum source, such as a vacuum pump (not shown), by respective fittings 468, 470 (FIGURE 31) and conduits 471, 472. Therefore, each bore 450 and the vacuum cup 453 associated therewith is placed into fluid communication with the vacuum source from the time the port 450 is placed into fluid communication with the slot 465 until the port passes beyond the slot 467, it being noted that the bridging portion 466 is narrower than the diameter of the port 450 and the vacuum is not broken 60 during the transition of the port 450 from the slot 465 to the slot 467. Due to this construction a vacuum is drawn through each vacuum cup 453 from the time the face of the vacuum cup is generally parallel to the path of travel of the packages P' upon the pulley belt 361 65 (FIGURE 22) until the vacuum cup 453 has reached the position shown in FIGURE 23 at which time the vacuum is broken by the associated port 450 passing beyond the slot 467 and being brought into fluid communication with atmosphere as the port 450 passes a downwardly directed flange 470 (FIGURE 32) of a member 471 adjustably carried by the plate 460. By shifting the member 471 to the left or to the right as viewed in FIGURES 29 and 30 the point at which vacuum cut-off occurs can be 70 75 decreased or increased, respectively.

At the termination of the reorientation operation, each latched package P' is transferred to the upper runs (unnumbered) of a pair of conveyor chains 475, 476 each having transversely aligned generally L-shaped lugs 477 (FIGURES 22, 25, 26 and 33). The conveyor chain 475 is entrained about sprockets 478, 480 which are fixed to respective shafts 481, 482 conventionally journaled in the side plates 365, 366 of the frame 26. The conveyor chain 476 is similarly entrained about sprockets 483, 484 fixed to the respective shafts 481, 482. The shaft 482 is the drive shaft for the chains 475, 476 and includes a sprocket 485 about which is entrained a drive chain 486. The drive chain 486 is also entrained about a sprocket 487 fixed to the shaft 391 which is driven in the manner heretofore described to impart left-to-right movement of the upper runs of the chains 475, 476 to advance the latched packages P' past two mechanisms 500, 501 which insert closure members or enclosures E into axially opposite open end portions of each of the packages P'. Referring first to FIGURE 35 of the drawings, the closure E includes an end panel 502 defined by a bottom edge 503, an upper fold line 504 and a pair of side fold lines 505, 506. A top flap 507 is joined to the central panel 502 along the fold line 504 while side flaps 508, 510 are joined to the central panel 502 along the respective fold lines 505, 506. The side flaps 508, 510 are notched respectively at 511, 512 to define respective hooks 513, 514.

The mechanisms 500, 501 are positioned on opposite sides of the chain conveyors 475, 476, as is best illustrated in FIGURE 33 of the drawings. Only the mechanism 500 is completely illustrated in the drawing because the mechanism 501 is identical thereto and the following description of the mechanism 500 is equally applicable to the mechanism 501.

The mechanism 500 includes three vertically upstanding frame members or plates 525, 526 and 527 (FIGURES 1-B and 33). The plates 525, 526 and 527 are secured to the frame 26 by conventional means, and are maintained in generally vertical parallel relationship, as is best illustrated in FIGURE 1-B of the drawings.

A hopper 528 (FIGURES 1-B, 34, 36 and 37) is supported by suitable frame members between the plates 525, 526 above the level of the chains 475, 476 (FIGURE 4) and the latched packages P' (FIGURE 34). A plurality of the closures E are supported in the hopper 528 in stacked relationship and are prevented from accidental removal therefrom by gate defining members 530, 531 (FIGURE 34). While stacked in the hopper 528 the closures E are completely flat and the edges 503 thereof are positioned more closely adjacent the conveying chain 476 than the terminal flap 507 (FIGURE 33).

Means in the form of a pair of plates 532, 533 (FIGURES 34 and 37) secured to the hopper 528 are provided for folding the side flaps 505, 506 generally normal to the central panel 502 as each closure E is individually removed from the hopper 528 by closure removing means in the form of a pair of vacuum transfer arms 535, 536. The plates 532, 533 are spaced apart a distance slightly greater than the distance between the fold lines 505, 506 (FIGURE 37) whereby each side flap 508, 510 is deflected to a normal position as each closure E is withdrawn from the hopper in a downwardly and leftward direction by the vacuum transfer arms 535, 536 in the direction of the unnumbered headed arrows associated therewith in FIGURES 36.

The vacuum transfer arms 535, 536 each carry a pair of vacuum or suction cups 537 placed in fluid communication with a conventional vacuum source (not shown) by an associated conduit 538 and a conventional cam operated vacuum control valve 540 (FIGURE 1-B) supported by a bracket 541 which is in turn fixed to the plate 526. The vacuum control valve 540 is operated by a cam disk 542 fixed to a shaft 543 which is journaled for rotation in the plates 525, 527. The vacuum control valve 540 includes a pivotally mounted arm 544 (FIGURE 34) spring biased

5 in a counterclockwise direction to continually urge a cam follower or roller 545 into contact with a cam surface (unnumbered) of the cam 542. The cam surface of the cam 542 is contoured to draw a vacuum over the flow path heretofore defined through the vacuum cups 537 when the same are positioned as shown in FIGURE 34 in contact with the lowermost closure and to terminate or cut off the vacuum as the vacuum transfer arms 535, 536 reach the position thereof shown in solid lines in FIGURE 36 of the drawings.

10 The cam 542 and the shaft 543 are rotated in the direction of the unnumbered headed arrow in FIGURE 34 by means of a sprocket 546 fixed to the shaft 543. A chain 547 is entrained about the sprocket 546 and a sprocket 548 fixed to an output shaft 550 of a conventional gear box 551. The input to the gear box 551 is by means of a chain 552 (FIGURE 1-B) entrained about a sprocket (not shown) of the gear box 383 and a sprocket 553 of the gear box 551.

15 The vacuum transfer arms 535, 536 are pivoted between the phantom and solid outline positions shown in FIGURE 36 of the drawings by means of a shaft 555 which is journaled for rotation in the plates 525-527 (FIGURE 1-B). The shaft 555 includes an end portion (unnumbered) to which is attached a short crank arm 556 (FIGURE 36). A rod 557 is pivotally connected to the crank arm 556 by a pivot 558, and an opposite end portion of the rod 557 is pivoted at 560 to an arm 561 pivotally connected at 562 to the plate 527 at a point slightly above the shaft 543 (FIGURES 1-B and 36). The arm 561 carries a cam roller or follower 563 which rides upon a surface 564 of a cam 565 fixed to the shaft 543. The arm 561 is normally biased in a counterclockwise direction (FIGURE 36) by a spring 567 secured to the arm 561 and the plate 527 (not shown).

20 Assuming that the vacuum transfer arms 535, 536 are in the solid line position shown in FIGURE 36, the rotation of the cam 564 in a clockwise direction by means of the rotation imparted to the shaft 543 through the sprocket 546 presents a low cam portion (not shown) of the cam 565 to the follower 563. The spring 567 draws the arm 561 in a counter-clockwise direction pulling the rod 557 downwardly and pivoting the crank arm 556 counter-clockwise in FIGURE 36. This counter-clockwise pivoting similarly swings the shaft 555 and the vacuum transfer arms 535, 536 secured thereto in a counter-clockwise upward direction to the phantom line position in FIGURE 36. At this time the vacuum cups 537 are in fluid communication with the vacuum source and the lowermost closure E in the hopper 528 is gripped thereby. As the high side of the same surface 564 contacts the follower 563 the arm 561 is rotated clockwise about the pivot 562 against the bias of the spring 567. The rod 557 is moved upwardly causing clockwise rotation of the crank arm 556 about the shaft 555 and similar movement to the vacuum transfer arm 535, 536 to the solid position shown in FIGURE 36.

25 Each closure E is thereafter transferred from the vacuum transfer arm 535, 536 to a vacuum transfer arm 570 (FIGURES 36 and 37) which is normally positioned between the vacuum transfer arms 535, 536 (FIGURE 37). The vacuum transfer arm 570 is carried by a reciprocal support mechanism, generally designated by the reference numeral 575, which moves the vacuum transfer arm 570 in synchronism with the packages P' as the latter are continuously advanced by the chain conveyors 475, 476. The vacuum transfer arm 570 includes a pair of vacuum cups 571 connected to a conventional vacuum source (not shown) by a conduit 572 and a conventional control valve 573 (FIGURE 1-B) actuated by a cam 574 (FIGURE 45) fixed to the shaft 543. The valve 573 includes a pivotally mounted arm 579 having a follower 576 in contact with a cam surface 577 of the cam 574. A spring (not shown) at all times maintains the follower 576 biased toward and against the cam

surface 577 of the came 574. The cam surface 577 is contoured to open the valve 573 and place the vacuum cups 571 in fluid communication with the vacuum source when the vacuum transfer arm 570 is in the position illustrated in FIGURE 36 and cuts off fluid communication with the vacuum source when the vacuum transfer arm 570 is in a vertical upright position (FIGURE 34). This movement causes a transfer of the closures E from the vacuum transfer arms 535, 536 to the vacuum transfer arm 570 and the subsequent insertion of each closure E into the adjacent axial open end portion of the package P', as shown in FIGURE 34 of the drawings.

The vacuum transfer arm 570 is reciprocated between the solid outline positions shown in FIGURES 34 and 36 by a crank mechanism which includes a shaft 580 (FIGURES 33, 36 and 37) journaled for rotation in the plates 525, 527 (FIGURE 38). The shaft 580 carries a crank arm 581 positioned between the plates 526, 527 (FIGURE 33). The crank arm 581 is pivoted to an arm 582 (FIGURE 36) which is in turn pivoted to an arm 583. The arm 583 is pivoted at 584 to the plate 526 and is normally spring biased in a counter-clockwise direction (FIGURE 36) by a spring 585. The arm 583 carries a cam follower or roller 586 which is at all times maintained in rolling contact with a cam surface 587 of a cam 588 fixed to the shaft 543.

The vacuum transfer arm 570 is reciprocally mounted upon the shaft 580 by the support mechanism 575 in a manner best illustrated in FIGURES 37 and 38 of the drawings. The reciprocal support mechanism 575 includes, in addition to the vacuum transfer arm 570, an upstanding arm 590 slidably mounted on the shaft 580 by a bushing 591. A pair of pins or rods 592, 593 secure the arm 590 and the vacuum transfer arm 570 in fixed relationship to each other thereby assuring simultaneous sliding and pivoting movement of these arms in a manner which will be more apparent hereafter.

A flanged collar 594 is fixed to the shaft 580 and the pins 592, 593 are mounted for reciprocal sliding movement in bushed bores 595, 596, respectively, of the collar 594.

Assuming the vacuum transfer arm 570 is in the position illustrated in FIGURE 36 of the drawings, clockwise rotation of the cam 588 presents a low side of the cam surface 587 to the follower 586 causing the arm 583 to be biased counter-clockwise as viewed in FIGURE 36 by the spring 585. Counter-clockwise pivoting of the arm 583 pivots the crank arm 581 and the shaft 580 in a clockwise direction, again as viewed in FIGURE 36. As the shaft 580 rotates clockwise the flanged collar 594 (FIGURES 37 and 38) fixedly secured thereto also rotates clockwise imparting clockwise rotation to both the arm 590 and the vacuum transfer arm 570 through the rods 592, 593. The vacuum transfer arm 570 is thereby pivoted clockwise to the solid position illustrated in FIGURE 34 during which movement a closure E carried thereby is inserted in an associated package P'. Continued rotation of the cam 588 reverses the direction of movement of the vacuum transfer arm 570 in a manner readily apparent from FIGURE 36 causing reverse movement of the vacuum transfer arm 570 from the position illustrated in FIGURE 34 to that shown in FIGURE 36.

As each closure E is introduced into an associated package P' guide means 600 (FIGURES 34 and 36-38) are provided for guiding each closure E into an associated package P'. The guide means 600 includes a pair of guide plates 601 and 602 (FIGURE 39) secured to respective arms 603, 604 joined together at lower end portions by a cross-bar 605 (FIGURE 34). The arms 603, 604 and the crossbar 605 define a generally U-shaped structure (FIGURE 37) which is secured by an arm 606 (FIGURES 34, 37) to a sleeve 610 mounted for sliding movement relative to the shaft 580 between the solid and phantom outline positions shown in FIG-

URE 38. The sleeve 610 does not rotate relative to the shaft 580 and the plates 601, 602 of the guide means 600 are at all times maintained in the positions thereof shown best in FIGURES 34 and 39 of the drawings adjacent the conveyor chain 476. The plates 601, 602 preferably converge toward each other and are spaced from each other a distance corresponding to slightly less than that of the distance between the side panels of the carrier blanks B. Thus, as each closure E is carried by the vacuum transfer arm 570 through the plates 601, 602 the respective side flaps 510, 508 contact the inner surfaces of these plates and are guided between the carrier blank side panels and the articles A, as is best illustrated in FIGURES 34 and 39 of the drawings.

During the insertion of each closure E into an associated package P', it is important that the lower end portion (unnumbered) of each closure adjacent the edge 503 is fully inserted into the package to prevent the closures from inadvertently falling out of the packages upon the retraction of the vacuum transfer arm 570, and to assure that the hook portions 513, 514 of the closures E are positioned adjacent the blank apertures 178 to permit the subsequent interlocking engagement therebetween, as will be apparent hereafter. The vacuum transfer arm 570 is therefore provided with a crossbar 609 at the ends of which are attached pusher elements 611, 612. The pusher elements 611, 612 are in generally parallel relationship and of a length to contact the lower end portion of each closure E during the insertion thereof into an associated package P', as shown in FIGURE 39. The function of the pusher elements 611, 612 is augmented by another pusher element 613 of a plate 614 carried by the upstanding arm 590 (FIGURES 38 and 39). Thus, each closure E is inserted into an associated package P' by the vacuum elements 571, the pusher elements 611, 612 carried by the vacuum transfer arm 570 and the pusher element 613 carried by the upstanding arm 590 of the support mechanism 575.

At the same time a closure E is inserted into one of the packages P' the hook portions 513, 514 of a closure previously inserted in a leading package are interlocked with the carrier blank apertures 178 and the top flap 507 of the closure is bent about the fold line 504 toward the interior of the package by a mechanism 625 (FIGURES 37 and 40). The mechanism 625 includes a pair of generally parallel bars 626, 627 secured to each other by a cross plate 628 which is in turn fixed to the arm 590. The lower end portions (unnumbered) of the bars 626, 627 include oppositely directed projections 630, 631, respectively. The projections 630, 631 carry identical pusher elements 632 (FIGURE 40) which forcefully engage the lower edges of the closures and urge the hook portions 513, 514 to a position beyond the edge of the apertures 178 causing the hook portions 513, 514 to subsequently engage the side panels in the manner best illustrated in FIGURE 41 of the drawings. During the same operation a pair of pusher elements 635, 636 carried by the upper end portions of the respective bars 626, 627 contact the top flap 507 to force the same toward the interior of the respective package (FIGURE 40).

As is heretofore noted, the support mechanism 575 and the various components carried thereby are reciprocated in directions parallel to the direction of travel of the packages P' through the mechanism 500. The reciprocal movement of the support mechanism 575 to the right as viewed in FIGURE 37 in synchronism with the packages P' is necessary to assure that each closure E is properly guided into an associated package by the guide means 600 and the vacuum transfer arm 570, and that a previously inserted closure E is properly interlocked with a leading package and the flap thereof deflected inwardly by the mechanism 625.

The support mechanism 575 is reciprocated by imparting reciprocal movement to the sleeve 610 which includes a reduced end portion 640 received in a bore 641 of the

vacuum transfer arm 570. The reduced end portion 640 of the sleeve 610 includes an outwardly opening circumferential groove 642 (FIGURE 38) in which bottoms a screw 643. This connection between the vacuum transfer arm 570 and the sleeve 610 permits simultaneous reciprocal movement of each, as well as similar movement of the support mechanism 575, and also permits pivoting movement of the vacuum transfer arm 570 because of the free circumferential movement of the screw 643 in the groove 642.

The sleeve 610 includes an enlarged end portion 646 (FIGURE 45) carrying radially outwardly directed diametrically opposite pins 647, 648 (FIGURE 38). The pins 647, 648 are received in respective elongated slots 650, 651 (FIGURE 46) of a bifurcated lever 652. The lever 652 carries a cam follower or roller 653 and is mounted for pivoting movement in a horizontal plane by a pivot pin 654. The pivot pin 654 is secured to a bracket 655 which is in turn fastened to the plate 526. The lever 652 is biased in a counter-clockwise direction as viewed in FIGURE 33 by a spring 656 connected between the lever 652 and the plate 525.

The cam follower 653 is received in a cam slot or track 657 of a barrel cam 658 fixed to the end of a shaft 660. The shaft 660 is journaled for rotation in the plates 526, 527 (FIGURE 1-B). A sprocket 661 is fixed to the shaft 660 and entrained about the sprocket 661 and a sprocket 662 fixed to the shaft 543 is a chain 663. Rotation of the shaft 543 in the manner heretofore described imparts rotation to the sprocket 662, the chain 663, the sprocket 661, the shaft 660 and the barrel cam 658 carried thereby. Rotation of the barrel cam 658 causes clockwise pivoting movement of the bifurcated lever 652 as viewed in FIGURE 45 of the drawings against the bias of the spring 656 to urge the sleeve 610 and the supporting mechanism 575 connected thereto to the right in timed relationship with the movement of the packages P' until the sleeve 610 reaches the rightmost terminal position thereof (FIGURE 8). The spring 656 thereafter returns the sleeve 610, the support mechanism 575 and the components carried thereby to the left as viewed in FIGURE 38 until the sleeve 610 reaches the phantom outline position in the same figure.

The final operation performed by the apparatus 25 is that of deflecting a portion of each carrier blank top panel into overlying relationship to an associated closure flap by a mechanism, generally designated by the reference numeral 670 (FIGURES 1-B, 33, 43 and 44). The mechanism 670 includes an arm 671 (FIGURE 3) which is floatingly pivoted on the shaft 555. That is, the shaft 555 functions solely as a pivot for the arm 671 and reciprocal movement imparted to the shaft 555 in the manner heretofore described in no way imparts movement to the arm 671. The arm 671 includes a forward end portion (unnumbered) to which is secured a plate 672 having a pair of pins 673 (FIGURE 33) directed toward the conveyor chains 475, 476. The arm 671 and the pins 673 carried thereby are normally disposed slightly above the top panels of the packages P' being conveyed past the mechanism 500.

An arm 674 is pivoted to the arm 671 at 675, and an opposite end portion of the arm 675 is pivoted at 676 to an arm 677. The arm 677 is pivoted to the vertical plate 525 at 678 (FIGURE 43) and carries a cam follower or roller 680. The cam follower 680 contacts a cam surface 681 of a cam 682 fixed to the shaft 543. The arm 677 is biased by a spring 683 in a counter-clockwise direction as viewed in FIGURE 43 of the drawings to maintain the follower 680 in constant contact with the cam surface 681 of the cam 682.

As a package approaches the position of the rightmost package P' in FIGURE 38, the clockwise rotation of the cam 682 as viewed in FIGURE 43 by the rotation of the shaft 543 causes the follower 680 to contact and ride against the low portion (unnumbered) of the cam track

5 681. The spring 683 abruptly draws the arm 677 counter-clockwise which pivots the arm 671 clockwise through the arm 674. The pins or elements 673 are thereby moved downwardly into contact with the projecting portion (unnumbered) of the top panel and deflects the same downwardly into overlying relationship to the terminal flap of an associated closure E as shown in FIGURE 44 of the drawings.

10 As each of the completed packages P' passes beyond the mechanisms 500, 501 each package is transferred to the upper runs (unnumbered) of two chains 690, 691 (FIGURES 1-B and 33). The chains 690, 691 are entrained about sprockets 692, 693, respectively, which are carried by a shaft 694 conventionally journaled in the frame 26. 15 The sprocket 692 is fixed to the shaft 694 while the sprocket 693 is free to rotate relative to the shaft 694, i.e., is floatingly mounted thereon. An end portion (unnumbered) of the shaft 694 projecting through the frame 26 carries a drive sprocket 695. The chains 690, 691 are entrained about similar sprockets (not shown) carried by a shaft 696 (FIGURE 1-B) having an end portion to 20 which is fixed a drive sprocket 697. The sprocket carried by the shaft 696 about which the chain 690 is entrained is floatingly connected to the shaft 696 while the 25 other sprocket is fixed to the shaft 696. This construction of the sprocket permits the chain 690 to be driven at a faster speed than the chain 691 whereby each package is again rotated or reoriented through 90 degrees in such a manner that the axis of each package is subsequently 30 positioned in parallel relationship to the direction of travel of the chains 690, 691.

The chains 690, 691 are driven by a take-off from the drive chain 486 (FIGURE 1-B) which is entrained about a sprocket 700 fixed to a shaft 701 journaled for rotation 35 in the frame 26. The chain 486 rotates the shaft 701 in a clockwise direction and another sprocket fixed thereto (not shown) in a similar direction. A chain 702 is entrained about the other sprocket fixed to the shaft 701 and a sprocket 703 fixed to a shaft 704 projecting forwardly (FIGURE 1-B) of a housing 705. A chain 706 is entrained about a sprocket 707 fixed to the shaft 704 and the sprocket 695 imparting clockwise rotation to the sprocket 695 and left-to-right movement of the upper run (unnumbered) of the chain 690.

40 45 The opposite end portion (not shown) of the shaft 704 projects rearwardly of the housing 705 and carries a sprocket (not shown) about which is entrained a chain 707. The chain 707 is also entrained about a sprocket 708 fixed to a shaft 710 projecting rearwardly of a housing 711. Another chain 712 is entrained about the sprocket 697 and a sprocket 713 fixed to the shaft 710 to drive the shaft 696 and the chain 691 through the sprocket (not shown) about which the chain 691 is entrained. A guide 715 adjacent the chain 691 prevents reorientation of the packages P' beyond a point at which the axes thereof are 50 parallel to the direction of travel, as is readily apparent from FIGURE 33 of the drawings.

55 60 While preferred forms and arrangement of parts have been shown in illustrating the invention, it is to be clearly understood that various changes in details and arrangement of parts may be made without departing from the spirit and scope of the invention as defined in the appended claimed subject matter.

I claim:

65 1. An apparatus for forming a package from a plurality of articles and an apertured carrier blank comprising means for conveying a plurality of articles along a predetermined path, means for wrapping a carrier blank about selected ones of the articles, and means for at least temporarily supporting the articles through apertures of the carrier blank during the formation of the package.

70 75 2. The apparatus as defined in claim 1 wherein means are provided for moving said supporting means through the carrier blank apertures into supporting relationship with the articles during at least a portion of the travel of

the articles along the predetermined path, and means for retracting the supporting means after the carrier blank has been completely wrapped about the articles.

3. The apparatus as defined in claim 1 including means for moving said supporting means in the same direction as said articles along the predetermined path.

4. The apparatus as defined in claim 1 wherein said supporting means enter the apertures from opposite sides of the predetermined path, and said support means further define means for engaging edges of the apertures for aligning any misaligned carrier blank during the wrapping thereof.

5. The apparatus as defined in claim 1 including means along opposite sides of the predetermined path for engaging edges defining the apertures whereby the carrier blank is urged into intimate relationship with the articles, and means for moving said engaging means towards each other to urge the blank into intimate relationship with the articles.

6. The apparatus as defined in claim 1, wherein said supporting means are defined by a pair of endless members having adjacent runs, a plurality of supporting elements carried by said endless members, said supporting elements being disposed in a generally common plane, means for driving said endless members to move said adjacent runs in a predetermined direction, said adjacent runs having entrance and exit end portions, means at said entrance end portions for moving the supporting elements of the adjacent runs toward each other for entering the apertures of the carrier blank and supporting the articles therethrough, and means at said exit end portion for moving the supporting elements of the adjacent runs away from each other for leaving the apertures of the carrier blank after the latter has been wrapped about the articles.

7. The apparatus as defined in claim 6 wherein said last two-mentioned means are defined by respective converging and diverging portions of the respective entrance and exit portions of the adjacent runs.

8. An apparatus for forming a tight package from a plurality of articles and a carrier blank having a plurality of apertures each defined by an edge of a portion of the carrier blank comprising means for conveying a plurality of articles along a predetermined path, means for wrapping the carrier blank about selected ones of the articles, means for engaging the edges of the apertures on opposite sides of the predetermined path, means for moving the engaging means toward each other to tightly wrap the carrier blank about the selected articles, and means for securing portions of the carrier together after the engaging means have been actuated to form a tightly wrapped package.

9. The apparatus as defined in claim 8 wherein said engaging means are defined by a pair of endless members having adjacent runs, a plurality of engaging elements carried by said endless members, said engaging elements being disposed in a generally common plane, means for driving said endless members and move said adjacent runs in a predetermined direction, said adjacent runs having entrance and exit end portions, means at said entrance end portion for moving the engaging elements of the adjacent runs toward each other for contacting said edge portion and tightly wrapping the carrier blank about the articles, means for securing together portions of said blank prior to the movement of the engaging elements away from each other, and means at said exit end portion for moving the engaging elements of the adjacent runs away from each other after the portions of the carrier blank have been secured together.

10. A method of forming a package from a plurality of articles and a generally planar carrier blank having apertured panels comprising the steps of conveying the plurality of articles along a predetermined path, wrapping selected ones of the articles in the carrier blank by folding the carrier blank to a generally tubular configuration, supporting the selected articles through the apertures of the

panels during at least a portion of the time during which the wrapping takes place, and securing together panels of the carrier blank to complete the package.

11. A method of forming a package from a plurality of articles and a generally planar carrier blank defined by panels at least some of which have apertures defined by associated edges comprising the steps of conveying the plurality of articles along a predetermined path, moving the carrier blanks generally along said predetermined path, wrapping selected ones of the articles in the carrier blank by folding the carrier blank toward a generally tubular configuration, aligning the carrier blank and the selected articles by transversely inserting at least a single finger-like element into an aperture at each side of the articles thereby contacting the aperture edges to cause the carrier blank to shift if the same is initially misaligned, and securing together panels of the carrier blank to complete the package.

12. Apparatus for forming a package from a plurality of articles, a carrier blank and a partition comprising means for conveying a plurality of articles along a predetermined path, means for positioning a partition upon upper end portions of selected ones of the articles, means for wrapping a carrier blank about both the partition and the selected articles to a generally tubular configuration, means movable through openings in the carrier blank for supporting the selected articles during the wrapping of the carrier blank to form the package, and means for securing portions of the blank together to complete the formation of the package.

13. Apparatus for forming a package from a plurality of articles, a carrier blank and a partition comprising means for conveying a plurality of articles along a predetermined path, means for positioning a partition upon upper end portions of selected ones of the articles, means for wrapping a carrier blank about both the partition and the selected articles to a generally tubular configuration, said partition and the carrier blank including finger-receiving opening means, means for positioning the carrier blank relative to the partition with the finger-receiving opening means in alignment, and means for securing portions of the blank together to complete the formation of the package.

14. The apparatus as defined in claim 13 wherein said positioning means includes means for transferring each partition away from an associated hopper, said transferring means including a finger-like element which enters the partition finger-receiving opening means, and means for moving the finger-like element in synchronism with the movement of the selected articles and the carrier blank thereon.

15. The apparatus as defined in claim 14 including guide means for supporting each partition as it is being transferred to said selected articles.

16. The apparatus as defined in claim 14 wherein said transferring means is an endless conveyor carrying said finger-like element.

17. The apparatus as defined in claim 14 including guide means for supporting each partition as it is being transferred to said selected articles, and said transferring means is an endless conveyor carrying said finger-like element.

18. The apparatus as defined in claim 14 including guide means for supporting each partition as it is being transferred to said selected articles, said guide means are a pair of spaced guide bars along which said partitions slide during the transfer thereof to said selected articles, and said finger-like element moves between said guide bars during the transfer of the partitions to the selected articles.

19. Apparatus for forming a package from a plurality of articles and a carrier blank comprising means for conveying a plurality of articles along a predetermined path, means for wrapping a carrier blank about selected ones of the articles to a generally tubular configuration,

said carrier blank includes a plurality of openings in at least two panels thereof, means for transversely entering said openings and aligning said carrier blank during the wrapping thereof to assure securement of the blank portions and accurate housing of the articles in the package, and means for securing portions of the blank together to complete the formation of the package.

20. Apparatus for forming a package from a plurality of articles and a carrier blank comprising means for conveying a plurality of articles along a predetermined path, means for wrapping a carrier blank about selected ones of the articles to a generally tubular configuration, said carrier blank including a top, a pair of sides and a pair of closure panels and openings at junctures between adjacent side and closure panels, said apparatus further including means movable through said apertures for supporting the selected articles during the wrapping of the carrier blank to form the package, means for contracting edges of the blank defining said openings for urging the closure panels transversely of the predetermined path whereby the carrier blank is tightly wrapped about the selected articles, means for reorienting the package after the formation thereof, and means for inserting a closure member in each axially opposite end portion of the package after the latter has been reoriented.

21. The method as defined in claim 10 including the further step of tightening the carrier blank about the

selected articles by contracting the aperture edges and move the same toward each other.

5 22. The method as defined in claim 10 including the step of aligning the carrier blank and the selected articles by transversely inserting at least a single finger-like element into an aperture at each side of the articles thereby contacting the aperture edges to cause the carrier blank to shift if the same is initially misaligned.
